UNITED STATES PATENT OFFICE.

LAWRENCE J. FOX, OF NEW YORK, N. Y.

CLOTH-DRILLING MACHINE.

1,308,898.

Specification of Letters Patent.

Patented July 8, 1919.

Application filed November 3, 1917. Serial No. 200,188.

To all whom it may concern:

Be it known that I, LAWRENCE J. Fox, a citizen of the United States, and resident of the borough of the Bronx, in the city, 5 county, and State of New York, have invented a certain new and useful Cloth-Drilling Machine, of which the following is a specification.

The present invention relates to cloth 10 drilling machines, particularly to such machines intended for drilling or boring holes through a plurality of thicknesses of cloth which have been previously shaped by a cutting machine, although this is not necessary, the boring of the holes being for the 15 purpose of indicating the position of pockets or the like, which are to be sewed to the cloth. The mere drilling of a hole through the cloth with a nail as heretofore used, would not ordinarily provide a permanent marking, as the hole formed would close immediately after the drill is withdrawn. The present embodiment of the 20 invention proposes to rapidly revolve the drill 25 as it is forced through the cloth, so that the friction produced serves to burn the hole permanently.

It is an object of the present embodiment of the invention to provide a machine with 30 which holes may be bored and burned into the cloth accurately and in a convenient manner, requiring the use of only one hand, so that the other hand may be otherwise employed. To this end, I propose to provide 35 a machine having a slidable base, which may be engaged beneath the layers of cloth, and which will limit the movement of the needle after it is bored through the cloth, so that it cannot engage the table and drill a 40 hole therein. Other objects are simplicity of construction, and facility of operation, permitting of accurate control of the boring needle with one hand, and without requiring that the hand be moved from the handle. A 45 further object is an even disposition of the downward pressure exerted upon the needle during the boring operation, so that an accurate boring of the cloth results.

With these and other objects in view, an 50 embodiment of my invention is shown in the accompanying drawings, and this embodiment will be hereinafter more fully described with reference thereto, and the invention will be finally pointed out in the 55 claims.

In the accompanying drawings:

Figure 1 is a side elevation of an embodiment of my invention, showing the same in full lines in its position previous to boring holes through the cloth, and in dotted lines 60 in its final position, the dotted line position also indicating its normal position when not in use;

Fig. 2 is a plan view of the same;

Fig. 3 is a sectional view of the base portion of the device; and

Fig. 4 is a detail front view of the base and supporting post.

Similar reference characters indicate corresponding parts throughout the several 70 figures of the drawings.

Referring to the drawings, and more particularly to Fig. 1 and 2 thereof, the present embodiment of my invention, which is shown by way of example only, comprises 75 a base 7 bent downwardly at its marginal portions as at 7^a and provided in spaced relation at its under side with rollers 8 rotatable upon shafts 8^a journaled in the side portions of the base. The base is preferably 80 of the shape shown in Fig. 2, being straight at its forward edge and rounded at its rear edge, and is provided in the forward portion thereof with a flared opening 9.

The drawings represent the preferred embodiment of this invention. A movable base plate 7 is freely traversable over a work table and has a thin edge 7^a adapted to slide under a stack of cloth to be bored. This plate preferably is of the shape shown in 90 Fig. 2, being straight along its forward thin edge 7^a and rounded at its rear end. It is preferably constructed with a downward marginal flange 7^d which is beveled at the forward end to form the thin edge 7^a. 95 The base in its flanged form is also provided with rollers 8 disposed in spaced relation on its underside on shafts 8^a journaled in the side flanges of the base. The base plate is provided in its rear portion with a 100 threaded socket 7^b and near its thin or beveled edge with a flaring slot 9.

A post 5 is fixed to the base. This post may be detachable and in its preferred form 105 it is provided at its lower end with a screw-threaded tang 6 which engages the socket 7^b. This post is preferably angular and hollow in its upper portion and provided in one side in said upper portion with a vertical guide slot 12. A slot 12 is provided 110

in the post 5 to accommodate the member 4 in its downward movement.

At the outer end of the handle 2 there is provided a bracket 2^b, to which there is secured by means of rivets or the like 2^c, a vertically disposed motor 1. Current is supplied the motor through the wires 1^a, and is controlled by means of a switch 11, provided in the bracket 2^b, in such position, 10 that it may be conveniently operated by the thumb of the hand engaging the handle 2. This switch is preferably of the well known "push" type, the same being turned on, by pushing in one direction, and off, by pushing 15 in the other direction.

A drill head 1^b is fixedly secured to the shaft of the motor, and the drilling needle 10 is secured to the said drill head. It will be understood that the same may be readily 20 removed and sharpened or replaced, or a longer needle placed therein for the purpose of drilling an interior hole in the cloth, as will be hereinafter more fully pointed out. The needle 10 is in direct alinement 25 with the hole 9 of the base, and when the apparatus is in the dotted line position shown in Fig. 1, the point of the needle passes through the hole, but is prevented from further downward movement by a stop 30 5^a provided in the post 5, and which limits the downward movement of the support 3 and the parts carried thereby.

The operation of my drilling machine is as follows: The sliding base 7 is engaged 35 beneath the lowermost layer of the layers of cloth 14, these layers of cloth being in practice, about eight inches high. The needle 10 is placed upon the point of the uppermost layer at which it is desired to 40 drill a hole. Thereupon the current is turned on by the thumb pressing the switch 11, and the drill is pressed down by pressure being exerted upon the handle 2. The needle is preferably first engaged with the 45 cloth before the current is turned on, so that the same will not be disturbed from its proper alinement by centrifugal force. The boring is continued until the apparatus is stopped by engagement of the support 3 with 50 the stop 5^a. In this position, after all of the layers of cloth have been drilled through, the point of the needle is disposed in the opening 9 of the base.

The machine, it will be seen, is absolutely 55 steady during the drilling operation, being supported directly upon the cutting table, and as one hand is free, the same may be utilized for holding down the cloth. Also, as the handle is supported at this outer end 60 by the brace 4, great pressure upon the same will not tend to change the alinement of the needle, so that an absolutely straight

hole is bored. This is very important, as a slight change of the position of the needle will cause the hole to be bored in a different 65 position in the lower layers of the cloth than in the upper layers. Except in the case of an interior hole being bored in the cloth, it is not necessary to lift the same from the table, and with the rollers 8 it may be 70 readily slid to any position desired.

Where an interior hole is to be bored, the apparatus is placed upon the upper surface of the layers of cloth, and a longer 75 needle is secured in the drill head, this needle being of such length that it will bore a hole through the cloth beneath the base 7. The cloth at any interior point forms a very substantial support for the device, so that there will be no danger of the same 80 becoming unsteady.

I have illustrated a preferred and satisfactory embodiment of my invention, but it is obvious that changes may be made therein within the spirit and scope thereof, 85 as defined in the appended claims.

I claim:

1. A cloth drilling machine comprising a movable base plate freely traversable over a work table, and having a thin edge 90 adapted to slide under a stack of cloth to be bored, a post fixed to said base plate, a vertically movable support mounted on said post, a motor carried by said support, and a vertically disposed drilling needle operated by said motor.

2. A cloth drilling machine comprising a movable base plate freely traversable over a work table, provided with rollers on its underside and having a downward beveled 100 flange adapted to slide under a stack of cloth to be bored, a post fixed to said base plate, a vertically movable support mounted on said post, a motor carried by said support, and a vertically disposed drilling needle 105 operated by said motor.

3. A cloth drilling machine comprising a movable base plate freely traversable over a work table and having a thin edge adapted to slide under a stack of cloth to be bored, 110 a post fixed to said base plate, a vertically movable support mounted on said post, a motor carried by said support, and a vertically disposed drilling needle operated by said motor, said freely traversable base 115 plate having a needle slot opposite said drilling needle.

In testimony that I claim the foregoing as my invention I have signed my name in presence of two subscribing witnesses.

LAWRENCE J. FOX.
